DESIGN FOR A KNEE-HIGH ROLLER-COASTER

Walter T. Phillips and Margaret B. Phillips,
Louisville, Ky.

Application October 25, 1937, Serial No. 72,414

Term of patent 14 years

To all whom it may concern:

Be it known that we, Walter T. Phillips and Margaret B. Phillips, the above-named petitioners, both citizens of the United States and residents of Louisville, in the county of Jefferson and the State of Kentucky, have invented a new, original, and ornamental Design for a Knee-High Roller-Coaster, of which the following is a specification; reference being had to the accompanying drawing forming a part thereof.

In the drawing, Fig. I is a side elevational view of the knee-high roller-coaster showing my new design. Fig. II is a plan view of the same; and Fig. III is a rear elevational view thereof.

Our new design is characterized by a frame mounted on two tandem wheels; the dominant features of the design being a horizontal knee-trough swinging knee-high from said frame for holding the rider's knees, steering handles mounted on an encased steering rod in the front of said frame, and a low-hanging arch supporting a brake-lever and a foot-rest.

We claim:—

The ornamental design for a knee-high roller-coaster, as shown and described.

WALTER T. PHILLIPS.
MARGARET B. PHILLIPS.
